UNITED STATES PATENT OFFICE.

GEORGE MACLOSKIE, OF SCHENECTADY, NEW YORK, ASSIGNOR TO GENERAL ELECTRIC COMPANY, A CORPORATION OF NEW YORK.

COLLECTOR-OPERATING VALVE.

No. 888,339.

Specification of Letters Patent.

Patented May 19, 1908.

Application filed July 28, 1906. Serial No. 328,163.

To all whom it may concern:

Be it known that I, GEORGE MACLOSKIE, a citizen of the United States, residing at Schenectady, in the county of Schenectady and State of New York, have invented certain new and useful Improvements in Collector-Operating Valves, of which the following is a specification.

This invention relates to electric railways and especially to the apparatus mounted on an electric railway vehicle for collecting current from an overhead conductor or a third-rail. It is sometimes found to be advisable or necessary to operate one portion of a rail-way by means of current supplied by a trolley wire or overhead conductor, and another portion by current taken from a third-rail arranged near the roadbed. The moving vehicle must therefore be equipped with two or more current-collecting devices to co-operate with these two supply conductors. Means must be provided also for retracting the collecting devices, so that the idle one may rest out of the way and be prevented from striking any structure erected adjacent to the roadway.

The broad features of such a scheme have been disclosed by other inventors. My invention relates to an operator's valve which can be operated both automatically and manually to cause the retraction or the advance of a current collecting device. For the sake of convenience, I have illustrated it as applied to an overhead collector, but it is equally applicable to the shoe of a third-rail system.

In the accompanying drawing, Figure 1 is a diagram of piping and valves for pneumatically controlling the collectors; Fig. 2 is a longitudinal section, on the line 2—2, Fig. 3, of my improved collector-operating valve; Fig. 3 is a cross-section of the same on the line 3—3, Fig. 2; and Fig. 4 is a cross-section on the line 4—4, Fig. 2.

I have chosen to show two collectors and two valves, though it is evident that but one may be used, if desired. As they are both alike, a description of one will suffice.

The collector is preferably of the lazy-tongs variety. The shoe 1 slides in contact with the overhead conductor 2, which is provided with an elevated portion 3 at the point in the line where it is desired to retract the collector. The shoe is pivoted to the upper members 4 of two toggles, whose lower mem-

bers 5 are pivoted on a pedestal 6 mounted on the electric vehicle. The adjacent ends of the lower member 5 are provided with sector gears 5' which intermesh so that the members move in unison. The lower ends 60 of the upper members extend beyond their pivots, and strong springs 7 are attached thereto and to the lower members 6 at or near their pivots 6'. These springs urge the shoe upwardly against the conductor, the 65 shoe being electrically connected with the pedestal by flexible leads 8.

The pedestal is hollow and contains a cylinder 9 in which fits a piston 10 connected by a piston-rod 11 with a yoke 12 which 70 stands above the lugs 13 on the lower members of the toggles. A strong helical spring 14 is compressed between the top of the pedestal and the piston and urges the latter downward with a force amounting to several 75 hundred pounds; sufficient to overcome the upward thrust of the springs 7 and pull the shoe away from the conductor when the yoke presses down on the lugs 13.

The lower end of the pedestal is closed, as 80 by a screw-plug 15, so that a chamber is formed under the piston to which compressed air or other fluid can be admitted through a pipe 16. The area of the piston is sufficient 85 to enable the air to lift it against the tension of the spring and hold the yoke 12 out of engagement with the lugs 13.

The air is stored in a suitable reservoir and the pressure is maintained by any suitable air compressor (not shown). The admission 90 of the air to the cylinder in which the piston works, and its exhaust therefrom, are controlled by a valve located at some point on the vehicle convenient for the operator. Inasmuch as electric vehicles are usually arranged to run either end foremost, there is a valve at each end of the vehicle and each valve simultaneously controls both current collecting devices, if more than one is used. The construction of this collector operating 95 valve forms the subject-matter of the present application. Prior to my invention, it has been proposed to use a somewhat similar valve having a handle connected directly with the moving parts. But the objection to this was 100 that in case the valve was operated automatically, in the manner hereinafter described, the handle was thrown violently from one of its positions to the other, and would seriously injure the operator if it happened to strike 110

him. By my invention, the handle for operating the valve manually is not affected by the automatic operation of the valve, so that the danger of injuring is obviated.

5 The collector-operating valve has a casing 17 provided with a bushing 18 having a thickened central portion provided with a longitudinal groove 19. The casing is closed at each end by a screw-plug 20. In each end 10 of the casing is a piston 21, 22 rigidly connected by a rod 23. Between the hubs 24 of the pistons is a slide valve 25 of the D type, which seats in the groove in the bushing and has wings 26 extending up on each side of the 15 rod 23. A spring 27 is secured between said wings by pins 28 and bears against the wall of the bushing 18 opposite to the valve and thereby operates to hold the valve 25 in engagement with its seat in the groove 19. In 20 the lower side of the bushing 18 are an exhaust port 29 and a delivery port 30, and at the upper right-hand end of the bushing is an escapement port 31. Instead of extending the delivery port 30 directly through the casing 25 at the bottom side thereof, as diagrammatically indicated in Fig. 1, it is arranged so as to connect with a duct 32 made in the periphery of the bushing 18 and connects at the top thereof with a channel 33 which extends 30 near the left-hand end of the bushing. A supply port 34 enters the valve chamber at about the center of the front side of the bushing 18 after turning through a right angle in the casing and connects with a pipe 51 leading 35 from the supply of compressed air.

On the front side of the casing 17, near each end thereof, is arranged a tappet valve 35 with an extended stem and seating against a sleeve 36 threaded into the upper end of the 40 valve chamber 37. A spring 38 is interposed between the lower end of the valve 35 and the bottom of the chamber which operates to normally hold the valve in closed position. A tappet port 39 extends from each valve 45 chamber 37 into the respective cylinder in which the pistons 21 and 22 are located. A T-shaped hand-lever 40 is pivoted to a lug 41 at the top of the casing 17 and has an arm overlying each tappet valve 35 so that by 50 rocking the lever in one direction or the other the corresponding valve is forced from its seat.

The exhaust port 29 is connected to a drip-pipe 42 tapped into the casing 17 at 43. The 55 delivery port 30 is connected, as above stated, by way of duct 32 and channel 33 to a delivery pipe 44 tapped into the casing 17 at 45 and leading through a double check valve 46 to the lower end of the cylinder 9 in 60 the collector pedestal. The escapement port 31 is connected by a pipe 47 tapped into the casing 17 at 48 and extending up alongside of the collector pedestal where it is provided with a pilot valve 49 having its stem bearing 65 against a short lever 50 adapted to be en-

gaged by one of the arms 5 of the trolley when the latter is allowed to rise above its normal working level. It will be observed that the pistons 21 and 22 are not "packed" and accordingly their chambers will normally 70 be supplied with compressed air by leakage of the latter therearound. Accordingly when the pilot valve 49 is forced from its seat by lever 50 coming in contact with the trolley arm 5 the pressure to the right of piston 22 will be relieved, and as the pistons 21 and 22 move to the right under the expansion of air at the left of piston 21 the valve 25 will be moved from the position indicated in Fig. 2 to the right until it connects the upper 75 ends of ports 29 and 30 and thereby allowing the air in the collector cylinder 9 to escape and permitting the spring 14 to exert its force of recoil to retract the collector arms. 80

When it is desired to raise the collector to 85 working position, the hand lever 40 is thrown to the left to open the left-hand tappet valve 35 and permit the air to the left of piston 21 to escape to thereby effect the movement of the valve 25 to the left into the position shown 90 in Fig. 2, closing the exhaust port 29 and opening the delivery port 30 to the compressed air supplied through port 34.

Where two collectors are used on a vehicle, as indicated in Fig. 1, the delivery pipes 44, 95 16 and the pipes 47 leading to the pilot valves of both collectors are connected so that both collectors may be controlled by a single engineer's valve. In order to prevent the compressed air delivered from one collector-operating valve to its pipe 44 being exhausted through the other valve, a double 100 check valve 46 is interposed between the pipes 44 of the respective valves.

I do not desire to restrict myself to the 105 particular form or arrangement of parts herein described and shown, since it is apparent that they may be changed and modified without departing from my invention.

What I claim as new and desire to secure 110 by Letters Patent of the United States, is,

1. In current collecting apparatus for electric vehicles, a collector operating valve comprising a casing, a piston in said casing, a slide valve connected to said piston, means for normally maintaining balanced pressure on opposite sides of said piston, and hand-operated means for relieving the pressure on either side of the piston according to the direction it is desired to move the valve. 115

2. In current collecting apparatus for electric vehicles, a collector-operating valve comprising a casing, a piston in said casing, a slide valve connected to said piston, means for normally maintaining balanced pressures 120 on opposite sides of said piston, and tappet valves arranged at both ends of said casing for relieving the pressure on either side of said piston.

3. In current collecting apparatus for elec- 125

tric vehicles, a collector operating valve comprising a casing, a double ended piston in said casing, a slide valve disposed between the ends of said piston, means for normally maintaining balanced pressures on opposite ends of said piston and tappet valves at both ends of said casing for relieving the pressure on either end of said piston.

4. In current-collecting apparatus for electric vehicles, a collector operating valve comprising a casing, a double ended piston in said casing, a slide valve disposed between the ends of said piston, means for nor-

mally maintaining balanced pressures on opposite ends of said piston, tappet valves at 15 both ends of said casing for relieving the pressure on either end of said piston, and a double-ended lever pivoted to said casing and adapted to alternately engage said tappet valves.

In witness whereof, I have hereunto set my hand this 27th day of July, 1906.

GEORGE MACLOSKIE.
